The ornamental design for a hand truck, as shown and described.

DESCRIPTION

FIG. 1 is a left front isometric view of a first embodiment of a hand truck constructed in accordance with the present invention;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is a top elevational view of FIG. 1;

FIG. 7 is a bottom elevational view of FIG. 1;

FIG. 8 is a left front isometric view of a second embodiment of a hand truck constructed in accordance with the present invention;

FIG. 9 is a front elevational view of FIG. 8;

FIG. 10 is a rear elevational view of FIG. 8;

FIG. 11 is a right side elevational view of FIG. 8;

FIG. 12 is a left side elevational view of FIG. 8;

FIG. 13 is a top elevational view of FIG. 8; and,

FIG. 14 is a bottom elevational view of FIG. 8.
